UNITED STATES PATENT OFFICE.

JAMES W. WALLS, OF PUEBLO, COLORADO.

COMBINATION LOCKING SWITCH-STAND.

1,244,147.

Specification of Letters Patent. Patented Oct. 23, 1917.

Application filed September 10, 1913. Serial No. 789,127.

To all whom it may concern:

Be it known that I, JAMES W. WALLS, a citizen of the United States, residing at Pueblo, in the county of Pueblo and State 5 of Colorado, have invented certain new and useful Improvements in Combination Locking Switch-Stands, of which the following is a specification, reference being had therein to the accompanying drawing.

10 This invention relates to switch stands and has for its object the provision of a combination interlocking switch stand in which the operating lever will be automatically locked when the switch is thrown by 15 the downward movement thereof.

Another object of the invention is to provide a switch stand in which the switch rod is operated by a bell crank through the medium of a reciprocating rod mounted 20 vertically within the stand and moved by the operating lever in order to throw the switch.

A still further object of the invention is to provide a novel form of lock for the 25 switch lever which is so constructed that when the lever is thrown in a downward position, the operating arm thereof will be engaged by the movable bolt of the lock, in such a manner that it will be impossible for 30 the lever to be raised until the bolt is actuated by a key.

Other and further objects and advantages of the invention will be hereinafter set forth and the novel features thereof defined by 35 the appended claims.

In the drawings—

Figure 1, is a front elevation of my improved construction of switch stand;

Fig. 2, is a side elevation of the same;

40 Fig. 3, is a detail enlarged side elevation of the upper portion of the stand with parts removed; and

Fig. 4, is a section taken on the line 4—4 of Fig. 3.

45 Like numerals of reference refer to like parts in the several figures of the drawings.

In the drawings, 1 indicates a skeleton stand comprising a base 2 having legs 3 connected at their upper ends to a plate 4 50 forming a support for a head 5 which is in the form of a casting; said casting being provided with a vertical opening in alignment with a centrally depending tubular portion 6 of the plate 4 through which extends a tube 7 mounted at its lower end in a support carried by the base 2 of the stand.

Secured to the lower end portion of the tube 7 is a crank 8 which is provided with the ordinary means for connecting the same to the switch rod. 60

The legs 3 of the stand 1 are preferably arranged in pairs, as shown in the side elevation, and diverge at their lower ends between which is pivotally mounted a bell crank 9; one arm of which is bifurcated as shown at 10 in which is pivotally mounted a switch locking rod 11. The other arm of the bell crank is provided with a yoke 12 embracing a grooved sleeve 13 slidably mounted upon the tube 7; the arms of said 65 yoke being provided with pins 14 extending into the groove and forming a movable connection. 70

Slidably mounted within the tube 7 is a rod 15 having a transverse pin 16 arranged 75 therein adjacent its lower end which extends out through oppositely disposed slots 17 formed in the tube 7; the outer portions of which are secured in the collar 13 as clearly shown in Fig. 1, in order to form 80 a connection between the collar 13 and the rod. By connecting the rod to the collar in this manner, as the rod is reciprocated in the tube 7, the sleeve will be carried with it in order to oscillate the bell crank so as 85 to reciprocate the switch lock rod 7 in order to release and lock the switch, and while I have not illustrated a switch used in connection with this stand, it is of course understood that the connecting rod 11 is connected to the locking device of the switch 90 in the ordinary manner.

The casing 5 is provided with an enlarged portion 18 having a slot formed therein in which is pivotally mounted a switch lever 95 19 upon a pivot pin 20; said switch lever being provided with an extension forming an arm 21 having a rounded end 22 which extends through a slot 23 formed in the tube and is adapted to be seated within a recess 24 formed in the rod 15 in order to form a connection between the arm and rod in such a manner that when the lever 19 is raised, the rod will be forced downwardly 100 so as to operate the switch locking device. 105

The lever 19 is held from turning when in its lowered position by forming a notch 25 in the plate 4 into which the lever fits, as clearly shown. The casing 5 is provided with a pivoted spring-actuated bolt 26 110 notched as shown at 27 to embrace the arm 21 of the lever 19 in order to prevent the

lever from being raised until the movable bolt is swung out of the path of the arm, as will be later described.

A key hole 28 is formed in the casting 5 in which is arranged an eye pin 29 adapted to receive the tubular stem of a key which is provided with the usual form of bit adapted to engage a pin 30 formed on the movable bolt 26 so that when a key is in 10 position therein and is turned upon the eye pin, the bolt will be swung out of the path of the arm 21 of the lever 19 in order to allow the rod to be moved downwardly to release the locking device.

15 From the foregoing description it will be seen that the movable bolt is pivotally mounted upon the eye pin 29 which forms a guide for the key and that the bolt is provided with a spring which normally 20 holds the same in an extended position, which bolt is of such a shape that it will ride over the arm of the switch lever as the lever moves by it in the downward movement of the lever and the upward movement of the arm so that when the switch 25 lever is thrown back into its normal position, the extended arm thereof will be embraced by the movable bolt in such a manner that it will be prevented from moving in any way; making it necessary to swing the bolt out of the path of the arm through the medium of a key.

While I have not shown the form of key used in connection with this lock, it is of 35 course understood that a tubular stem key is employed with a bit of such a size that it will engage the pin 30 carried by the bolt so as to swing the bolt upon its pivot out of the path of the extended arm, and by lifting 40 the switch lever upwardly, the extended arm will force the rod 15 downwardly. The end of the bolt will engage the side of the extended arm so that when the lever is being swung back into its original position, it will 45 ride over the arm into the position shown in Fig. 3 and securely lock the lever.

In the drawing, I have shown a switch stand without the semaphore attachment, but it is of course understood that any suitable 50 form of signal device can be used in connection with the stand and connected in such a manner that the semaphore will be operated.

I claim:

55 1. A combination switch stand, comprising a base having a skeleton portion terminating in a plate provided with notches, of a head mounted upon said plate, a vertically disposed tube extending through said head 60 and plate having a bearing in the base of said stand, said tube being provided with oppositely disposed slots, a plunger working in said tube, a sleeve mounted upon said tube having a connection with said plunger 65 through said slots, a bell crank having a

connection with said sleeve, a crank arm fixed on said tube, and a lever for independently operating the crank arm of the tube and the bell crank connected to the plunger.

2. In a switch stand, a vertically movable 70 switch lever having an extension, a rod operated by said extension, a movable bolt arranged to intersect the path of travel of said extension, and a key for moving said bolt out of the path of travel of said extension. 75

3. A switch stand having a base provided with legs, a plate carried by said legs, a head mounted upon said plate provided with notches, a rod mounted in said head, a pivoted lever, an extension formed on said lever 80 having a sliding connection with said rod, and a spring-actuated bolt arranged to intersect the path of travel of said extension for locking said lever.

4. A switch stand, comprising a base having legs mounted thereon, a plate carried by said legs provided with a tubular portion, a head mounted upon said plate, a tube extending through said head and tubular portion and revolvably mounted in the latter, a plunger slidably mounted in said tube, a bell crank having a connection with said plunger, a switch locking rod having a connection with said bell crank, and a switch operating device operatively connected to said 95 revolvable tube.

5. A switch stand having a head in the form of a casting, a switch lever mounted upon said casting having an extension, a vertical rod having an opening to receive said 100 extension, a notched spring-actuated bolt arranged within said casting adapted to embrace said extension, a bell crank operated by said rod, and a switch locking device connecting rod connected to said bell crank. 105

6. A switch stand having a vertically arranged tube provided with a slotted portion, a sleeve mounted on said tube, a rod slidably mounted within said tube having pins extending through said slot connected to said 110 sleeve, a switch lever operatively connected to said rod, and a bell crank operatively connected to said sleeve having a switch locking device connecting rod connected thereto. 115

7. A switch stand having a vertically reciprocating rod, a bell crank operated by said rod mounted upon a horizontal pivot, a switch rod connected to said crank, a switch lever having a connection with said rod, and a pivoted spring-actuated bolt mounted in a plane at right angles to said switch lever and adapted to intersect the path of travel of said lever. 120

8. A switch stand having a movable operating rod, a bell crank having a connection with said rod, a switch lever for operating said rod, a notched spring-actuated bolt mounted in a plane at right angles to said switch lever and adapted to embrace said switch lever when in lowered position, and 125 130

means for moving said bolt out of the path of said lever.

9. A switch stand comprising a base having legs extending therefrom provided with a plate at their upper end, said legs being arranged in pairs and diverging at their lower ends, a head arranged upon said plate, a tube extending through said head mounted upon said base, a bell crank mounted between one pair of legs, a sleeve slidably mounted upon said tube operatively connected to one arm of said bell crank, a rod mounted in said tube having a connection with said sleeve, said rod being provided with a recess, a switch lever having an extension extending into said recess, and a movable bolt arranged in the path of travel of said extension.

10. A combination locking switch stand having a vertically movable switch lever provided with an extension, a notched pivotally mounted spring-actuated bolt arranged to intersect the path of travel of said extension, and a key for actuating said bolt.

11. In a switch stand, the combination with a switch lever having an extension, of

mechanism operated by the extension for reciprocating said rod, a pivoted key-controlled spring-actuated notched bolt mounted in a plane at right angles to said lever, and adapted to embrace said extension when said switch lever is in lowered position, and means for moving said bolt out of the path of travel of said extension.

12. A switch stand having a head provided with a key hole, an eye pin, a spring-actuated bolt pivotally mounted upon said eye pin provided with a notch, a lever provided with an extension adapted to be embraced by said notch, a pin carried by said bolt, a key adapted to embrace said pin for moving said bolt out of the path of said extension, a rod reciprocated by said extension, and mechanism operated by said rod for operating a switch locking device. 45

In testimony whereof I affix my signature in presence of two witnesses:
